ABRAHAM COATES, OF WATERTOWN, NEW YORK, ASSIGNOR, FOR ONE-HALF, TO JAMES MARTIN HUNT, OF SAME PLACE.

Letters Patent No. 97,881, dated December 14, 1869.

IMPROVEMENT IN VALVES FOR WATER-ENGINES.

The Schedule referred to in these Letters Patent and making part of the same.

To all whom it may concern:

Be it known that I, ABRAHAM COATES, of Watertown, in the State of New York, have invented a new and useful Improvement in Valves for Water-Engines; and I do hereby declare that the following is a full, clear, and exact description of the same, reference being had to the accompanying drawings, and letters of reference marked thereon, making a part of this specification, in which—

Figure 1 is a plan view of my improved valve;

Figure 2 is a transverse vertical section, in the line $x-x$, fig. 1; and

Figure 3 is a transverse vertical section through valve, valve-chest, and cylinder.

To enable those skilled in the art to make and use my invention, I now proceed to describe its construction and operation.

Similar letters in the drawings refer to like parts.

This invention is an improvement upon the valve shown in the water-engine patented by Coates and Osborn, May 12, 1863, which valve was simply a flat plate, with a transverse disk on each end.

The improvement consists in providing the said valve with certain additional surfaces, for the purpose of relieving it from the pressure of the water which acts against it.

A represents my improved valve, the same consisting of a flat plate a , of suitable dimensions, with a transverse disk, a' , at each end, of a size suited to the capacity of the valve-chamber, the said disks being provided with

central trunnions, which enter bearings provided in the end plates of the valve-chamber, so that the valve may properly oscillate.

As the plate a is set with its side opposite the induction-port B, it is obvious that it is subject to the full pressure of the water entering that port, which pressure, in an operative water-engine, is liable to be too great for the strength of the plate to resist.

To take off a portion of such pressure, therefore, I cast between the disks a' , and parallel with the plate a , two or more bars, $c c$, flush with the outer surface of the disks, and I leave a space, c' , between the two bars opposite the centre of the plate a , and correspondent with the induction-port, through which the water may pass, and spaces $c'' c''$, between the bars and the edges of the plate a , through which the water may pass alternately to the cylinder C.

Now it is clear that the water which enters the induction-port, and fills the spaces between the plate a and bars $c c$, expends a portion of its pressure upon the latter, all which portion the plate a is relieved of, and this is the end sought to be accomplished.

What I claim as new, and desire to secure by Letters Patent, is—

The valve A, consisting of the plate a and the bars $c c$, as and for the purpose described.

ABM. COATES.
